UNITED STATES PATENT OFFICE.

HARRY WATKINS WILD, OF CHISWICK, ENGLAND, ASSIGNOR TO W. H. S. LLOYD CO., OF NEW YORK, N. Y., A CORPORATION.

DESIGN FOR WALL-PAPER.

40,491.

Specification for Design.

Patented Feb. 1, 1910.

Application filed October 26, 1909. Serial No. 524,748. Term of patent 3½ years.

To all whom it may concern:

Be it known that I, HARRY WATKINS WILD, a subject of the King of Great Britain, residing at Chiswick, in the county of Middlesex, England, have invented a certain new, original, and ornamental Design for Wall-Paper, of which the following is a specification, reference being had therein to the accompanying drawing, forming a part thereof.

The figure is a view of a section of wall paper, showing my new design.

I claim:

The ornamental design for wall paper, as shown.

HARRY WATKINS WILD.
